ATTORNEY

UNITED STATES PATENT OFFICE.

SAMUEL JACOB, OF PHILADELPHIA, PENNSYLVANIA.

DESIGN FOR AN AQUARIUM.

41,977.

Specification for Design.

Patented Dec. 12, 1911.

Application filed December 22, 1910. Serial No. 598,863. Term of patent 7 years.

● *To all whom it may concern:*

Be it known that I, SAMUEL JACOB, a citizen of the United States, residing at the city of Philadelphia, in the county of Philadelphia and State of Pennsylvania, have invented a new, original, and ornamental Design for Aquariums, of which the following is a specification, reference being had to the accompanying drawing, forming part hereof.

Figure 1, is a perspective view, and Fig. 2, an end view of an aquarium showing my new design.

An aquarium embodying my design and illustrated in the accompanying drawing

projects from the wall and presents to the eye an appearance like that presented by a picture framed and suspended on a wall. This in contra-distinction to an aquarium that is let into the wall and the front of which is vertical and presents the appearance of a show window being substantially flush with the wall.

I claim:

The ornamental design for an aquarium as shown and described.

SAMUEL JACOB.
